UNITED STATES PATENT OFFICE.

JOHN REAM, OF JACKSONVILLE, FLORIDA.

SPAR-PROPELLER.

1,206,247.

Specification of Letters Patent. Patented Nov. 28, 1916.

Application filed July 12, 1913, Serial No. 778,734. Renewed April 19, 1916. Serial No. 92,314.

To all whom it may concern:

Be it known that I, JOHN REAM, a citizen of the United States, residing at Jacksonville, in the county of Duval and State of Florida, have invented new and useful Improvements in Spar-Propellers, of which the following is a specification.

This invention relates to propellers for boats, particularly to what is known as spar propellers, which type is characterized by one or more spars which are mechanically operated after the manner of a pole, at the rear or the sides of the boat, these spars being alternately engaged with and withdrawn from the bottom and serving to move the craft as they are thrust downwardly by proper draft rigging into engagement with the bottom or bed of the stream.

Propellers of this type are designed more particularly for boats used in streams of relatively shallow draft and artificial waterways.

My invention relates to this general type and has for its object to provide a series of spars and operating mechanism which will automatically thrust and withdraw the spar at regular intervals so as to give a continuous propulsion to the boat.

In order that the invention may be clear to those skilled in this art I have illustrated it in the accompanying drawings, in which—

Figure 1 is a side elevation of a portion of a barge or scow with my propelling mechanism attached. Fig. 2 is a plan view of the structure shown in Fig. 1. Fig. 3 is a detail view of one of the trip and clutch mechanisms. Fig. 4 is a detail view of the latching mechanism for the winding drum clutch. Fig. 5 is a detail sectional view of the cross head and track-way. Fig. 6 is a side view partly in section of a portion of the trackway, spar and cross head. Fig. 7 is a detail of the releasing mechanism for the clutch retaining latch.

Referring to the drawings by numerals like numbers indicating like parts in the several views 10 indicates a barge or scow of any ordinary construction having mounted thereon a suitable propeller supporting frame comprising uprights 11 and stringers 12 of any suitable size and dimensions. Supported by said framework are the spar supporting tracks 13, which, as shown extend from the rear end of the boat upwardly to the stringer 12 to which they are suitably secured, each track 13 being preferably

straight from its lower end through substantially two-thirds of its length, and then curving upwardly to its point of attachment to the stringer 12, this curvature of the track 13 giving the proper line of movement to the spar.

Each track 13 is made up of two opposed T-plates or beams 14 spaced slightly apart to form a way for a cross-head 15 formed of two U-shaped plates 16 which engage the horizontal flanges of the T-beams 14. Journaled in suitable bearings 17 on the cross-head 15 is a spar-supporting shaft 18, to which shaft the upper end of the spar 19 is swiveled by a pivot pin 20. By this construction a universal movement of the spar 19 is secured so that it may adjust itself to the various positions it assumes in operation.

Each of the spars 19, which are four in number in the present showing although a greater or less number may be used, is provided near its upper end with an eye bolt 21 to which is secured the draft rope 22 said draft rope passing over a guide pulley 23 on the deck of the barge and thence to a suitable winch or drum 24. Near its lower end or foot each of the spars is provided with an eye bolt 25 to which is connected a draft rope 26 which passes upwardly over suitable pulleys carried by the stringer 12, said draft rope 26 passing to a drum 27.

With this construction it will be seen that the spar 19 will be drawn upwardly by the draft rope 26 when the drum 27 is operated, and that when the drum 24 is operated draft will be put upon the rope 22 so as to thrust the spar 19 down against the bottom of the stream and exert a poling action to move the boat forward, the cross-head 15 traveling up and down the track 13. The drum 27 which lifts the spar is of greater diameter than the drum 24 which draws the spar downward, the purpose of which difference in diameter will be explained hereinafter.

The spar 19 has its lower end shod with metal and pointed as at 28 so as to give a sure grip on the bottom, and in order that the foot may properly engage even a bottom where the pointed foot 28 would be likely to slip I provide the spring plate 29 which is pivoted at 30 to the foot and braced by the frame 31 when in its open position. A spring 32 normally tends to depress the plate 29 toward the foot, but it will be obvious that when the point of the plate 29 engages the bottom and the spar is thrust down-

wardly the plate 29 when it engages the bottom may open to the position shown in full lines in Fig. 1 and get a sure hold on the bottom even though it be broken or rocky and of such character as that the point 28 of the foot would with difficulty engage it.

It is my purpose, as stated, to provide a boat with a number of these spars, although the invention may be practised by using only 10 one, and in order that these spars may work alternately and properly I provide locking mechanism and trips for the alternate spars or pairs of spars so that one spar or the coacting set of spars will automatically trip 15 and release the other spar or set of spars, throw the power on, and cause them to be thrust downwardly to perform the poling operation, the spars which have made their thrust being at the same time drawn back to 20 starting position, and I shall now describe this trip and actuating mechanism.

It has been heretofore pointed out that the lift and thrust haul ropes are wound upon drums or winches 27 and 24, respectively, these drums being stationed as shown in Fig. 2, on the deck of the boat. In the present instance I have shown four of these drums two for lifting the spars and two for forcing them downwardly; and the drums 25 are all preferably mounted as idlers on a single shaft 32 mounted in suitable bearings and driven from any source of power.

The lifting ropes 26 operate in pairs, one pair being coupled to the two outside spars 19 in the present arrangement and winding upon one of the drums 27 while the other pair coupled to the inner spars 19 wind on the other drum 27, it being my purpose to 30 operate the pairs of spars alternately, and by manipulating the spars as arranged in this showing, an even and smooth propelling action is secured.

It is obvious that timed mechanism must be provided to bring about the proper movement of the spars and this I accomplish by 35 provided each drum 27, 27, with a clutch-face 33 adapted to be engaged by a clutch 34 splined on shaft 32^a and having a spring lever 35 normally tending to throw out the 40 clutch.

The clutch lever 35 for the drum 27 which lifts the outer spars is connected by a pull-cord 36 with a slide-latch *a* having a projecting finger 37^a mounted on each track 55 13 upon which the inner spars slide and near the upper ends thereof, each in position to be engaged by a trip 37 on the cross-head 14 of one of the inner spars as it is thrust downward, or as shown 60 the cord 36 is divided and each strand passes over suitable sheaves 38 to similar latches *a*, *a*, on the two inner tracks. With this construction it will be seen that as either or both trips 37 pull the slide latches *a* 65 downwardly the clutch 34 will be thrown in,

a lever-holding latch 39 being provided to engage clutch lever 35 and retain clutch 34 in engagement with the clutch face 33 on the drum 27 and the drum 27 will immediately wind up the lifting ropes 26 and draw up 70 the outside spars 19.

To retain the spars in lifted position ready for the downward thrust I provide a spring latch 40 adapted to engage a lug 41 at the upper end of the spar automatically when 75 the spar comes to the limit of its upward movement, and in order to throw out the winding drum 27 which exerts the lifting pull on the rope 26 I provide a spring thrust rod 42 which is struck by the upper end of 80 the spar and throws a lever 43 which is coupled by a pull-cord 44 with the clutch lever holding latch 39. Immediately the latch 39 is withdrawn the spring lever 35 will unship the clutch 34 stopping the winding of the 85 drum 27 and the lifting of the spars 19 which have been lifted in readiness to descend and make their propelling thrust.

To release the lifted spars from their supporting latches 40 I provide a lever 45 90 which engages the latch 40 at its rear end, the other end of the lever 45 being connected by a pull cord 46 with a second latch *b* on the inner tracks near their lower ends similar to the latch *a* just described, and having a 95 finger 37^a lying in the path of the trip 37 so that when the trip in its movement downwardly strikes the latch *b* it will pull the cord 46, throw the lever 45, and lift the latch 40 out of engagement with the lug 41 100 at the upper end of the spar completely releasing the spar ready for its downward movement.

In order to at once apply the propelling power to the released spar I provide a third 105 latch *c* below latch *b* similar to those just described which is engaged by the trip 37 from which latches *c* a divided cord leads over suitable sheaves to the clutch lever 47, of the power drum 24 on which the draft 110 ropes 22 for moving the spars downwardly are wound, these draft ropes 22 being shown in the present instance as connected to the outer spars of the four shown. When the clutch lever 47 is thrown to engage the 115 clutch 48 with the clutch face 49 on the drum 24 for the outer spars it will be latched by a latch 50 similar to the lever latch 39, the said latch 50 being coupled by means of pull cord 51 with a fourth latch *d* on the 120 track way 13 similar to the latches *a*, *b* and *c* and below them. This latch *d* when it is struck by the trip 37 on a spar serves to pull the lever-latch 50, release the spring-clutch lever 47 and throw out the clutch members 125 48 and 49 of the drum 24 that is thrusting the spar carrying said trip downwardly, thus stopping said winding drum 24.

The latches *a*, *b*, *c* and *d* are here shown as mounted upon one side of the track 130 130

a set of latches on each track. The latches *a* which unship the winding drums 27 are near the top of the tracks, the latches *b*, *c* and *d* are grouped near their lower ends, 5 this arrangement being necessary for the proper functioning of the spars. The several latches are each normally held in the position shown in Fig. 3 by the spring 52 which maintains them in this normal position until they are pulled downwardly by 10 the engagement of the trip 37 on the spar with the toe of the latch; the trip 37 and the latch toe being engaged, when the curved face 52^a strikes the incline 53 on the side of 15 the track-way; it will throw the latch *a* to the position shown in dotted lines in Fig. 3, a spring 54 returning the latch *a* to its normal position after the trip has passed. All 20 the latches are provided with fingers 37^a for convenience of operation.

The trips 37 on the cross heads have on one side an inclined face, as shown in Fig. 3, which on the lifting and return of the 25 spar strikes a similarly inclined face on the toe of the latch, whereupon the latch *a* will swing outward without pulling the cord, and thus the cross head will slide freely past the series of latches, all of which are 30 of the same construction, without jamming or breaking of the parts.

It will be understood that both of the 35 lifting drums 27 and both of the power drums 24 are provided with clutch levers and latch connections as above described, the clutch levers and releasing latches being so correlated as that the pair of outer spars will alternate with the pair of inner spars in lifting and thrusting, although it will be obvious that the connections may be arranged to give any combination of pairs 40 of spars that may be desired.

Such changes as are within the range of 45 mechanical skill may be adopted without departing from the spirit of my invention, as the present disclosure is merely illustrative and not restrictive of the same.

The operation of the invention in brief is as follows: Assuming the parts to be in the position indicated in Figs. 1 and 2, the 50 spars moving in the direction indicated by the arrows, that is, the inner spars descending and the outer spars ascending and near the completion of their upward movement. The ascending spars move faster than the 55 descending spars because their pulling rope is operated by drum 27 of greater diameter than the drum 24 upon which the downwardly thrusting ropes are wound. The outer spars will therefore reach the limit 60 of their upward movement, strike the thrust rods 42 and disengage the drum 24 before the inner spars reach the latches *b*. The outer spars are held in their upward movement for a short time by the latches 40 or 65 until the descending spars operate the

latches *b* whereupon the latches 40 disconnect the elevated outer spars and they drop by gravity to the bed of the stream, which as will be seen from Fig. 1 is a very short distance. The outer spars will remain in 70 this position a very short while dragging upon the bed of the stream until one of the latches *c* on the tracks of the inner thrusting spars is operated by said spar to engage the clutch members 48 and 49 of the drum 75 24 upon which is wound the rope for thrusting the outer spars downwardly, whereupon these outer spars will at once begin to operate and drive the boat forward. The two sets of spars now move downwardly at the 80 same speed, the inner spars travel but a short distance farther when they operate the latches *d* to disconnect the drum 24 by which they are being thrust downwardly. The inner spars thereupon cease to operate 85 and are dragged momentarily along the bottom of the stream or until the outer spars actuate the latches *a* which occurs almost immediately to couple the drum 27 upon which is wound the elevating rope 26 for 90 the inner spars, whereupon the said inner spars are drawn upwardly slipping past the latches in succession without operating them in the manner heretofore described, and moving upwardly at a much faster speed 95 than the outer spars descend, quickly reach their upper limit of movement and operate the thrust rods 42 to disconnect the elevating drum 27 and engage with the locking latches 40.

I claim:

1. In a propeller of the class described, the combination with a plurality of propelling spars, of mechanism for lifting said spars, separate means for exerting a downward thrust on said spars, and independent automatic means to separately throw said lifting and thrusting mechanisms into and out of operation.

2. In a propeller of the class described, the combination with a plurality of propelling spars, of independent mechanisms for lifting and for exerting a downward thrust on said spars, said mechanisms being timed to operate said spars alternately in two groups, tripping mechanisms operated by the downward movement of the spars of each group to connect the elevating mechanism for the spars of the other group, then connecting the mechanism for drawing said spars downwardly and finally disconnecting their own downwardly thrusting mechanism, and means operated by the upward movement of the spars for disconnecting their elevating mechanism.

3. In a propeller of the class described, the combination with a plurality of propelling spars, of independent mechanisms for elevating and for exerting a downward thrust on said spars, said mechanisms being

100

105

110

115

120

125

130

- timed to operate said spars alternately in two groups, separate means actuated by the spars of each group on their downward movement to successively throw the lifting mechanism of the other group into operation, then the thrusting mechanism of said group into operation and finally disconnecting its own thrusting mechanism, and means actuated by each spar upon the completion 5 of its upward movement for disconnecting the elevating mechanism of its own group.
4. In a propeller of the class described, the combination with a plurality of propelling spars, of independent mechanisms for lifting and for exerting a downward thrust on said spars, said mechanisms being timed to operate said spars alternately in two groups, mechanism for temporarily locking each spar in its elevated position, separating means actuated by the spars of each group on their downward movement to successively throw the lifting mechanism of the other group into operation to raise the spars thereof into engagement with said 15 locking mechanism, then unlocking said spars, then throwing the downwardly thrusting mechanism of said group into operation and finally disconnecting its own downwardly thrusting mechanism, and means actuated by each spar upon the completion of 20 its upward movement for disconnecting the elevating mechanism of its group.
5. In a propeller of the class described, the combination with a plurality of propelling spars, of cross heads to which the said spars are pivotally connected, guiding tracks for said cross heads, mechanism for lifting said spars, mechanism for exerting a downward thrust on said spars, and means on said 25 tracks in the path of movement of said spars to alternately throw said lifting and thrusting mechanisms into and out of operation.
6. In a propeller of the class described, the combination with a plurality of propelling spars, cross heads to which said spars are connected for universal movement, guiding tracks for said cross heads, mechanism for lifting said spars, mechanism for exerting a downward thrust on said spars, and spring latches on said guiding tracks in the path of movement of said spars to alternately throw said lifting and thrusting mechanisms into and out of operation.
7. In a propeller of the class described, the combination with a plurality of propelling spars, cross heads to which said spars are connected for universal movement, guiding tracks on which said cross heads slide, mechanism for lifting said spars, mechanism for exerting a downward thrust on said spars, and a series of latches on said guiding tracks adapted to be tripped by said spars to alternately throw said lifting and thrusting mechanisms into and out of operation.
8. In a propeller of the class described, the combination with propelling spars, of cross-heads connected with said spars for universal movement, guiding tracks for said spars, means for lifting and thrusting said spars, means for retaining a lifted spar in its upper position, and means actuated by movement of a thrust spar to release said lifted spar.
9. In a propeller of the class described, the combination with propelling spars, of cross-heads connected with said spars for universal movement, guiding tracks for said spars, power-mechanism for lifting said spars, power-mechanism for thrusting said spars, means for retaining a lifted spar in its upper position, means actuated by movement of a thrust spar to release said lifted spar, and means actuated by a thrust spar to apply power to said lifted spar.
10. In a propeller of the class described, a plurality of spars, power-mechanism for lifting said spars, and means actuated by a lifted spar for throwing said power-mechanism out of action.
11. In a propeller of the class described, a plurality of spars, power-mechanism for lifting said spars, a clutch controlling said power-mechanism, and trip mechanism in the path of a lifted spar to actuate said clutch mechanism.
12. In a propeller of the class described, a plurality of spars, power-mechanism for lifting said spars, power-mechanism for thrusting said spars, clutch devices to control said lifting and thrusting means, and trip mechanisms in the path of said spars to control said clutch devices.
13. In a propeller of the class described, alternately rising and falling spars, guiding tracks for said spars, winding drums to lift said spars, winding drums to give said spars a downward thrust, clutch mechanisms for said winding drums, and trip mechanisms in the path of movement of said spars to alternately clutch and unclutch said lift and thrust drums.
14. In a propeller of the class described, alternately rising and falling spars, guiding tracks for said spars comprising opposed T-trails, cross-heads universally coupled to the upper ends of said spars sliding in said track-ways, a winding drum for lifting said spars, a winding drum for giving a downward thrust to said spars, clutch devices controlling said drum, and trip mechanisms on said tracks in the paths of said spars to operate said clutch devices.
15. In a propeller of the class described, a propelling spar, a guiding track for said propelling spar having a straight lower section and a curved upper section, and power-mechanism for lifting and thrusting said spar.
16. A propelling spar having its lower

- end provided with a fixed engaging point, and an engaging foot pivoted to the under side of said spar adjacent said engaging point and projecting therefrom at an angle.
- 5 17. A propelling spar having its lower end provided with a fixed engaging point, a foot pivoted to the underside of said spar adjacent said engaging point adapted to swing perpendicular thereto when thrust 10 against the bottom of a stream, and a spring for pressing said foot when disengaged toward the underside of said spar.
- 15 18. A propelling spar having its lower end provided with a fixed engaging point, a foot pivoted to said spar adjacent the under side of said engaging point, and a rigid support against which said foot is pressed and by which it is sustained when 20 in its open position.
- 20 19. In a propeller of the class described, a plurality of guiding tracks, propelling spars mounted for reciprocation on said tracks, winding drums for lifting said spars, winding drums for exerting a downward 25 thrust on said spars, clutch devices controlling said winding drums, spring-retract-
- ed latches on said guiding tracks connected with said clutch devices, trips on said spars to actuate said spring latches, and means to disengage said trips and latches at a pre- 30 determined point.
20. In a propeller of the class described, a plurality of guiding tracks, propelling spars mounted for reciprocation on said tracks, winding drums for lifting said spars, 35 winding drums for exerting a downward thrust on said spars, clutch devices controlling said winding drums, spring-retracted latches on said guiding tracks connected with said clutch devices, trips on said spars 40 to actuate said spring latches, and a latch-engaging lug to throw said latch and disengage it from said trip device at a predetermined point.
- In testimony whereof I have hereunto set 45 my hand in presence of two subscribing witnesses.

JOHN REAM.
